UNITED STATES PATENT OFFICE.

MARK S. LEVERING, OF PHILADELPHIA, PENNSYLVANIA, ASSIGNOR TO
THE STANDARD HOSE MENDER AND PIPE COUPLER COMPANY, OF
CAMDEN, NEW JERSEY.

DESIGN FOR A MEMBER FOR AN AIR-BRAKE COUPLING.

SPECIFICATION forming part of Design No. 33,129, dated August 28, 1900.

Application filed July 18, 1900. Serial No. 24,109. Term of patent 14 years.

To all whom it may concern:

Be it known that I, MARK S. LEVERING, a citizen of the United States, residing at the city of Philadelphia, in the county of Philadelphia and State of Pennsylvania, have invented and produced a new and original Design for a Member for an Air-Brake Coupling, of which the following is a specification, reference being had to the accompanying drawings, forming part hereof, in which—

Figure 1 is a top plan view of a member of an air-brake coupling, showing my new design. Fig. 2 is an underneath plan view thereof. Fig. 3 is an end elevational view, and Fig. 4 is a side elevational view of the member.

As shown in the drawings, the leading or material feature of my invention consists of the cylindrical end *a* of the member, which is notched or slit, as at *b*, and which incloses a concentrically-arranged tube *d*, which is unnotched and provided with an annular rounded projection, as at *e*. As illustrated in Fig. 1, the member presents the appearance of a series of concentric rings *f*, partly surrounded by the segmental piece *g*, and from the rings *f* project the wings *k*, of triangular outline. Merging into the wings *k* is the cylindric end *a*, notched, as at *b*, and disclosing at the notches the interior tube *d*. When viewed in underneath plan, as at Fig. 2, the member presents the appearance of a cup *m*, having the rim *m'*, partly extending around the periphery of the cup, and a rib *m*², bifurcating the rim *m'* and extending inward toward the center of the cup *m*. From the cup projects the segmental piece *g* and the wings *k* and also a nipple-like projection *n*. The cup *m*

merges into a flattened extension *o*, which in turn merges into the cylindric end *a*. As viewed in end elevation, as at Fig. 3, the member presents the appearance of two concentric tubes *a* and *d*, of which the outer tube *a* is divided into a series of segments *a'* and the inner *d* has a rounded end *e*. Above the two tubes *a* and *d* projects or extends the convex and flat flange constituting the wings *k*, and from one side of the tubes *a* and *d* projects the rounded and flattened body which constitutes the cup *m*. When viewed in side elevation, as at Fig. 4, the member presents the appearance of a short cylindrical projection *a*, slit at one end, as at *b*, and disclosing at the slitted portion a second interior cylinder *d*, having a rounded or beaded end *e*. From the unslit end projects the wings *k* and box-shaped cup portion *m*, which carries the segmental piece *g*. The wings *k* merge by a rounded connection *k'* into the cylinder *d*; but the box-shaped cup *m* merges into the cylinder *d* between the outlines of the peripheral walls of said cylinder.

Having thus described my invention, what I claim as new, and desire to secure by Letters Patent, is—

The design for a member of an air-brake coupling, substantially as herein shown and described.

In testimony whereof I have hereunto set my signature in the presence of two subscribing witnesses.

MARK S. LEVERING.

Witnesses:

J. WALTER DOUGLASS,
THOMAS M. SMITH.
